UNITED STATES PATENT OFFICE

JOSEPH JACOBSON AND MICHELE FERRANDINO, OF PORTLAND, OREGON

MEASURING SUGAR BOWL

Application filed April 9, 1928. Serial No. 268,657.

This invention relates to improvements in sanitary measuring sugar bowls.

The principal object of the invention is to provide a sugar bowl for restaurant or domestic use including apparatus of simple and practical construction which will measure a predetermined quantity of sugar at each operation and deliver a like quantity for the added convenience of the user and for the prevention of contamination of the sugar by the use of individual spoons.

A further object of the invention is the provision of measuring and delivering apparatus for sugar including a spring-pressed plunger bar through which, on its downward stroke, the sugar contained in an intermediate measuring chamber is delivered to the cup of the user or wherever desired, and upon the return stroke of the plunger as actuated by a spring, the sugar flows from the container into said chamber for delivery at the next operation.

Other objects and advantages of our invention, and objects relating to details of construction and arrangement of parts, will be readily apparent in the course of the detailed description to follow.

The accompanying drawings illustrate by way of example a preferred form of our invention, in which:

Figure 1 is a view in vertical section of a measuring sugar bowl embodying our invention showing the operating mechanism enclosed therein in side elevation.

Fig. 2 is a detached fragmentary view of said operating mechanism in vertical section.

Fig. 3 is a partial plan view as indicated by line 3—3 of Fig. 2, parts of the mechanism being broken away.

Fig. 4 is a cross-sectional view on line 4—4 of Fig. 2.

Fig. 5 is a view in vertical section on line 5—5 of Fig. 2.

Referring to said views, the reference numeral 1 indicates an exterior casing of our improved sugar bowl formed of metal preferably of polished and ornamental appearance, such as silver plate, adapting it for use on a dining table. Said casing may be supported on legs 2 and is provided with a handle 3.

The inner compartment 5 of the casing is closed at its upper end by a screw-threaded lid 6 which is formed centrally with a circular depressed flange 7 having an inwardly directed annular ledge 8 at its lower end upon which the outwardly flanged rim 10 of a sugar container 11 is supported axially within the casing chamber 5. The flange 7 is internally screw threaded for the reception of a lid 12 screwed thereto through which access may be had to the container 11. The side walls of said container converge toward its lower end to a neck 13 protruded within the upper end of a measuring barrel 15, said neck having an open passage through which the sugar is supplied to said barrel at all times.

A vertically disposed frame bar 16 is rigidly secured at its upper end to the lid 6 and adjacent the handle, 3, and at its lower end bears, as at 17, upon the circular wall of the casing. At said bearing the frame bar extends horizontally in a frame arm 18 past the center vertical axis of the casing, where it is apertured, as at 20, to receive the barrel 15, which is rigidly connected thereto. Spaced from its upper end said barrel is provided with a horizontal partition 21, the side walls of the barrel extending upwardly above said partition, as at 22, to provide a recess 23 within which the neck 13 of the sugar container is received. Spaced downwardly from the partition 21 another horizontal partition 25 is formed between which and the partition 21 a measuring chamber 26 is enclosed. Below the partition 25 the side walls of the barrel are converged enclosing a delivery chamber 27 and leading to a restricted opening 28 directing the sugar as it is delivered to the user into the upper end of a spout 30 whose lower open end extends through the casing at a convenient point for delivery of the sugar into the cup of the user.

Each of the partitions 21 and 25 is formed with a slotted guideway 31 and 32 respectively, extending through the wall of the barrel directly over the frame arm 18. Slide plates 33 and 35 are slidably mounted in said guideways, respectively. The partition 21 is formed with an aperture 36 at its rear edge in symmetrical alignment with the slide plate 100

33. The partition 25 is formed with a similar aperture 37 at its forward end in symmetrical alignment with the plate 35. An inclined partition 38 is fixedly secured in the chamber 26 inclined downwardly from a point below the aperture 36 toward the aperture 37 to direct the sugar received in said chamber toward the latter opening, the capacity of the chamber 26 above said partition being sufficient to contain a teaspoonful of sugar or any other predetermined quantity. The slide plate 33 is formed with an aperture 40 in line with the aperture 36 to register therewith when said slide shall be restricted, as indicated in Fig. 2, and which is its normal inoperative position, so that sugar from the container 11 will flow into the chamber 26.

41 indicates an arm supported from the frame bar 16 in whose outer end a rocking lever 42 is pivoted at its middle portion, as at 43. The upper extremity of said lever is received in a slot 45 in the rear end of the side plate 33, and the lower extremity of said rocking lever is received in a slot 46 in the projecting end of the lower slide plate 35. A bell crank 47 is pivotally mounted in lugs 48 rigidly supported on the frame arm 18, of which lever one arm 50 is received in a slot 51 at the rear extremity of the slide plate 35 and its other arm 52 extends into a slotted opening 53 in the lower end of the frame bar 16.

The plunger bar 55 is guided for vertical reciprocating movements in the arm 41 and the lid 6 and is formed at its upper projecting end above the lid 6 with a button 56 within convenient reach, to be depressed by a finger of the hand of the operator, holding the sugar bowl by the handle 3. A collar 57 is rigidly connected to the plunger bar at its upper end within the container, and a coil spring 58 is mounted upon said bar somewhat under tension between the arm 41 and the collar 57 with which its opposite ends engage. The lower end of said plunger bar is formed with an eye 60 through which the arm 52 of the bell crank 47 extends.

It will be seen that, when the plunger 55 is depressed by the finger of the operator in opposition to the spring 58, it will actuate the bell crank arm 52 downwardly and cause the other arm 50 to retract the slide plate 35 to open the aperture 37 to admit of the escape of the sugar in the chamber 26 into the delivery chamber 27 and thence into the spout 30 for use. At the same time the retraction of the plate 35 through the engagement of the rocking lever 42 therewith will cause its upper arm, which is engaged in the slot 45, to push the slide plate 33 forwardly and thus close the aperture 36 while the lower aperture 37 is open. When the sugar from the chamber 26 has been emptied, the operator will release the button 56, whereupon the plunger bar will be forced upwardly by the

spring 58, causing the plate 35 to close the opening 37, while at the same time the rocking bar 42 will retract the plate 33 to its original position, as indicated in Fig. 2, bringing the apertures 36 and 40 into register, allowing the sugar from the container 11 to flow therethrough and fill the measuring chamber 26. Thus at each downward actuation of the plunger a measure of sugar from the chamber 26 will be delivered, and upon its return stroke the lower outlet from said chamber will be closed and its inlet opened to renew the measured quantity of sugar in said chamber. The container 11 may be readily refilled with sugar from time to time by the opening of the lid 12, and, when desired, may be readily removed for cleansing purposes. The operating mechanism is accessible upon the removal of the container 11 or may be taken out of the container for inspection or repair, when desired.

From the foregoing description, taken in connection with the accompanying drawings, the advantages of the construction and application of our improved measuring sugar bowl will be readily apparent; but, while we have described the principle of operation of the invention, together with the devices which we now consider the best embodiment thereof, it will be understood that the structures shown are merely illustrative and that such changes may be made therein as will lie within the scope of the following claims.

Having described our invention, what we claim, is:

1. In a measuring sugar bowl, consisting in an exterior casing, a sugar container removably mounted in said casing, said container having a converging outlet, a measuring barrel mounted in said casing arranged to receive the contents of said container, said barrel having a pair of transverse partitions having an entrance and outlet aperture therein, respectively, a partition in said measuring barrel inclined from the upper aperture to the lower aperture so as to direct the flow of sugar towards the lower of said apertures, slotted guideways formed within the transverse partitions, plates slidably mounted in said guideways normally closing the lower of said apertures, the upper of said plates having an aperture registering with said entrance aperture when the lower of said apertures is closed, a rocking arm engaged with both of said plates to slidably actuate them in opposite directions to alternately open and close said apertures, a bell crank operatively connected to the lower plate, a plunger bar connected to said bell crank, and a spring tending to retain said plunger bar in its uppermost position.

2. A measuring sugar bowl, consisting in an exterior casing, a sugar container removably mounted in said casing, a measuring barrel at the lower end of said container, a

horizontally disposed partition in said barrel having an aperture at one edge, a plate slidable in said partition having an opening therein normally adapted to register with said aperture, a lower partition in said barrel having an aperture at its edge opposite said aperture, in the upper of said partitions, a plate slidable in said lower partition, arranged to normally close the lower aperture, 5 said partitions being spaced apart to provide a measuring chamber therebetween, an inclined partition in said chamber directing the contents towards said lower aperture, a frame bar vertically disposed within the casing, an arm supported from the frame bar, 10 a rocking lever pivoted at its middle portion and fastened to the end of the arm, the upper extremity of said rocking lever engaging in a slot in the rear end of the upper slide plate and the lower extremity of said rocking lever 15 engaging in a slot in the projecting end of the lower slide plate so as to slidably actuate the plates in opposite directions to alternately open and close the apertures, a frame 20 arm extending horizontally from the vertically disposed frame arm, a bell crank mounted pivotally on said frame arm and connected to the lower plate to actuate the same, a spring pressed plunger bar to actuate said bell crank, a spout extending from the measuring barrel through the casing at its lower 25 extremity.

JOSEPH JACOBSON.
MICHELE FERRANDINO.
